Albert Christian Richard

United States Patent Office.

ALBERT CHRISTIAN RICHARD, OF POINT LOOKOUT, TENNESSEE.

Letters Patent No. 72,681, dated December 24, 1867.

IMPROVED HAY-PRESS.

The Schedule referred to in these Letters Patent and making part of the same.

TO ALL WHOM IT MAY CONCERN:

Be it known that I, ALBERT CHRISTIAN RICHARD, of Point Lookout, in the county of Hamilton, in the State of Tennessee, have invented a new and useful Improvement in Hay-Presses; and I do hereby declare that the following is a full and exact description thereof, reference being had to the accompanying drawing, and to the letters of reference marked thereon.

The nature of my invention consists in providing a hay-press with vertical slots in its sides, by means of which I am enabled to depress the platen through a combination of bars, links, racks, and levers, in a simple, efficient manner, and at a small cost.

To enable others skilled in the art to make and use my invention, I will proceed to describe its construction and operation.

I construct my improved hay-press vertical, and of any suitable form adapted to my improvements, with platen and corresponding bottom, both slotted alike, to receive the bands or ties after the hay is sufficiently compressed. I make the upright framework of square timbers, a^1 , a^2 , a^3 , a^4 , a^5 , a^6 , and a^7 ; provided at both ends with long tenons, b^1 , b^2 , b^3 , b^4 , b^5 , b^6 , b^7 , b^8 , b^9 , b^{10} , b^{11} , b^{12} , b^{13} , and b^{14} , which tenons pass through the horizontal cross-timbers c^1 and c^2 , and are secured therein, each by a suitable wooden key. Between the uprights a^2 a^3 and a^5 a^6 , in one side of the press, and between the corresponding uprights in the opposite side of the press, I provide the vertical or longitudinal slots d^1 , d^2 , d^3 , and d^4 , for the purpose hereinafter mentioned. On the platen e , indicated by dotted lines on the drawing, are provided two timbers, f^1 and f^2 , which run transversely to the planks forming said platen e . When the platen e is placed on the hay to be compressed, the centres of the ends of these timbers f^1 and f^2 correspond with the vertical slots d^1 , d^2 , d^3 , and d^4 . In the vertical slots just mentioned I provide two horizontal bars of iron, g^1 and g^2 , of sufficient width and thickness to withstand the strain to which they are intended to be subjected in operating the press, as hereafter described. The sides of slots d^1 d^2 d^3 d^4 hold these bars always on their edges on the top and in the middle of the cross-timbers on the platen e . In the ends of the bars g^1 and g^2 which project outside of the slots d^1 , d^2 , d^3 , and d^4 , I make suitable notches on the upper edges. In the first notches, or those next to the slots d , I provide the peculiar double-eyed link h . This link h hangs loose on the bars g^1 and g^2 , and is so constructed that the hook formed at its lower extremity i always by its own gravity presses against the toothed rack j . In the second notches, near the extreme projecting ends of the bars g^1 and g^2 , is placed the double-eyed link k . This link is formed in such a manner that it does not interfere in its operation with the hooked link h . The lower end of link k is formed into a horizontal square seat, l , to receive the lever or bar, m . This lever m is made of iron, laid with steel at its extreme end, n , where it engages with the toothed rack j , and is provided with a notch, o , in its under side. This notch o fits over the horizontal seat l of link k . The toothed rack j is made of cast iron, which, to prevent wear, can be cast on a chill. It has flanges on its sides, near the teeth, to strengthen the latter, and in these flanges I make suitable holes, in sufficient number to bolt the rack j firmly on to the press, through the upright timber a^4 , and through the planking of the press. The planking of that part of the side of the press is firmly spiked on the three uprights a^3 , a^4 , and a^5 , so as to refer the application of the power simultaneously to all three of these uprights, and through them to the horizontal cross-timbers c^1 and c^2 , and further, through the two latter again to the remaining uprights a^1 , a^2 , a^6 , and a^7 . The two pairs of upright timbers a^1 and a^2 , and a^6 and a^7 , are likewise each united by the inner planking of the press. The effect of this construction of the sides of the press is such that all its parts, including the transverse bolts p^1 and p^2 , contribute to resist the power developed by the application of the lever m .

In this description of my invention I have specified mainly only that side of the press, with its appendages, which is visible in the drawing. It will be evident to any one skilled in the art, (and I desire to have it so understood,) that the opposite side of the press is exactly similar as the one described, and that it is provided with similar and corresponding devices.

The bottom of the press rests on the cross-timbers c^1 and c^2 by means of the square timbers g^1 , g^2 , g^3 , and g^4 . The sides are secured together by the cross-timbers r of the front and back planking u^1 and u^2 , which are provided for that purpose with long tenons and suitable keys, as shown in the drawing, and also by the cross-foundation timbers S^1 and S^2 , which are bolted to the timbers c^1 and c^2 . The doors for discharging the finished bale are constructed in any suitable manner, and provided with cross-bars t^1 and t^2 , which can be

released by moving the same vertically in the iron staples v^1 and v^2 , secured in the corner-posts of the press, or in any equivalent manner.

In order to remove my improved press from place to place, if desired, the same can be expeditiously taken down by removing the keys from the tenons which unite the two sides, and the bolts which pass through the foundation-timbers S^1 and S^2 . When so disunited my press is essentially portable, and easily handled.

In order to operate my improved press, I fill the same with hay, which is trodden down evenly by a person as it is being pitched in. The platen e is then placed on the top of the hay, the bars g^1 and g^2 are passed into the vertical slots d^1 , d^2 , d^3 , and d^4 , resting on top of the cross-timbers f^1 and f^2 of the platen e . Now the link h , provided with hook i , is hung on the bars g^1 and g^2 , and next the link k is likewise appended to said bars in the notches provided for that purpose. It is understood that the duplicate of links h and k are appended on the opposite ends of bars g^1 and g^2 , on the opposite side of the press. Now, a lever, m , is inserted in the seat in the lower extremity of the link h , resting in the notch o , also on both sides of the press. On depressing the two levers the platen e is forced down, one or more teeth of the toothed rack j , and held there by the action of the hooked links h . This operation of the levers m is repeated until the hay is compressed to the required size of the future bale.

What I claim as my invention, and desire to secure by Letters Patent, is—

The combination of the platen e , the bars g^1 and g^2 , the links h and k , or their equivalents, the toothed rack j , and levers m , all arranged and operating substantially as set forth.

ALBERT CHRISTIAN RICHARD.
